(57) **CLAIM**

The ornamental design for a baby stroller assembly as shown and described.

DESCRIPTION

FIG. 1 is a perspective view of the first part of baby stroller showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top plan view thereof;
FIG. 8 is a bottom plan view thereof;
FIG. 9 is a partial enlarged view of portion 9 in FIG. 1;
FIG. 10 is a perspective view of the second part of baby stroller showing my new design;
FIG. 11 is another perspective view thereof;
FIG. 12 is a front view thereof;
FIG. 13 is a back view thereof;
FIG. 14 is a left view thereof;
FIG. 15 is a right view thereof;
FIG. 16 is a top plan view thereof;
FIG. 17 is a bottom plan view thereof;
FIG. 18 is a perspective view of the third part of baby stroller showing my new design;
FIG. 19 is another perspective view thereof;
FIG. 20 is a front view thereof;
FIG. 21 is a back view thereof;
FIG. 22 is a left view thereof;
FIG. 23 is a right view thereof;
FIG. 24 is a top plan view thereof;
FIG. 25 is a bottom plan view thereof;
FIG. 26 is a partial enlarged view of portion 26 in FIG. 18;
FIG. 27 is a partial enlarged view of portion 27 in FIG. 19;
FIG. 28 is a perspective view of a fourth part of a baby stroller assembly showing my new design;
FIG. 29 is another perspective view thereof;
FIG. 30 is a right view thereof;
FIG. 31 is a left view thereof;
FIG. 32 is a front view thereof;
FIG. 33 is a back view thereof;
FIG. 34 is a top plan view thereof;
FIG. 35 is a bottom plan view thereof;
FIG. 36 is a partial enlarged view of portion 36 in FIG. 28;
FIG. 37 is a partial enlarged view of portion 37 in FIG. 28;
FIG. 38 is a partial enlarged view of portion 38 in FIG. 29;
(Continued)

FIG. 39 is a partial enlarged view of portion 39 in FIG. 29; FIG. 40 is a perspective view of a baby stroller showing my new design, in a combined state;

FIG. 41 is a perspective view of a baby stroller assembly shown in a combined state with the front cover removed; FIG. 42 is another perspective view shown in another combined state; and,

FIG. 43 is a perspective view of a baby stroller assembly shown in a combined state with the front cover removed and a second row of seats added.

The broken lines depict portions of the baby stroller and form no part of the claimed design.

The dot dash line is included for the purpose of illustrating the bounds of the enlarged view and forms no part of the claimed design.

The claim is directed to a baby stroller assembly comprised of the four parts shown in FIGS. 1-39 and a final part that is identical to the seat part shown in FIGS. 18-27.

1 Claim, 43 Drawing Sheets
